UNITED STATES PATENT OFFICE.

JAMES E. PATTON, JR., OF MILWAUKEE, WISCONSIN.

INTERCHANGEABLE-COLOR-EXHIBITING DEVICE.

SPECIFICATION forming part of Letters Patent No. 572,216, dated December 1, 1896.

Application filed July 6, 1896. Serial No. 598,065. (No model.)

To all whom it may concern:

Be it known that I, JAMES E. PATTON, Jr., a citizen of the United States, and a resident of Milwaukee, in the county of Milwaukee and State of Wisconsin, have invented certain new and useful Improvements in Interchangeable-Color-Exhibiting Devices; and I do hereby declare that the following is a full, clear, and exact description thereof.

10 My invention relates to devices for exhibiting contrasting colors or paints; and it consists in certain peculiarities of construction and combination of parts, as will be fully set forth hereinafter and subsequently claimed.

15 In the drawings, Figure 1 is a front view of my device. Fig. 2 is a view of the same extended or open and partially broken away. Fig. 3 is a transverse sectional view, and Fig. 4 is a perspective rear view.

20 The object of my invention is the production of a convenient means for aiding in the selection of suitable colors to be employed in painting a house, and to that end I have devised a construction employing a series of

25 color-cards, which cards are movable and interchangeable and are combined with so much of the representation of a building as will give proper effect to the color scheme, whereby changes can be instantly made and varied indefinitely until a combination satisfactory to the would-be purchaser is effected.

30 Referring to the drawings, A represents the base, formed, preferably, of cardboard, which may be embossed or built of several layers of paper, as preferred, so as to have a central depression *a*, surrounded by a frame *b*. Within this depressed portion are arranged the color-cards B C D, which are all of the same size and shape and are removable and interchangeable. There may be any number of these cards, each one having a different tint or color, as indicated in the drawings by the difference in shading. These cards are all oblong pieces, but in Fig. 2 they are shown partly broken

35 away to show the depressed part *a*, within which they rest. From the described frame *b* of the base A, which frame is usually a separate layer, there preferably project inward tongues *c c*, beneath which the color-cards

40 are slipped to better retain them in place. To one end or edge of the base A there is hinged the cover E, which bears upon its outer surface the representation of a house or

other building. This cover is further formed with an opening *d* therein, so that when the 55 cover is closed down upon the base, as in Fig. 1, the said opening extends from the top of the roof down to the foundation of the house, and, when the color-cards are in place, gives an excellent idea of the colors employed, respectively, for the roof, the "body" of the house, and the "trimmings." It will be seen that the cards can be quickly changed and a new combination color effect instantly produced.

65 On the back of the base is secured an envelop F, the flap *e* of which is shown raised in Figs. 1 and 4, and this envelop forms a receptacle for the color-cards, of which there should be as many as there are colors or shades 70 of building-paints. The entire device forms a neat and convenient article, and one of great utility for all dealers in paints and for their customers.

Having thus described my invention, what 75 I claim as new, and desire to secure by Letters Patent, is—

1. An interchangeable-color-exhibiting device comprising a base, a series of removable and interchangeable color-cards, and a cover 80 having a pictorial representation on the outer face thereof, and an opening therethrough whereby, when the cover is closed upon the base, a portion of each color-card is displayed to complete the picture, substantially as set 85 forth.

2. An interchangeable-color-exhibiting device, comprising a base having a depressed center and a surrounding frame with tongues projecting oversaid center, a series of removable and interchangeable color-cards fitting within said center, beneath said tongues, a cover hinged to the base, and having a mutilated or partially-cut-away picture on its outer face, and a receptacle for the color-cards 95 secured to the back of the base, substantially as set forth.

In testimony that I claim the foregoing I have hereunto set my hand, at Milwaukee, in the county of Milwaukee and State of Wisconsin, in the presence of two witnesses.

JAMES E. PATTON, JR.
